UNITED STATES PATENT OFFICE.

JOHN TAYLOR, OF MOOREFIELD JUNCTION, WEST VIRGINIA.

FRUIT-DRIER.

SPECIFICATION forming part of Letters Patent No. 244,337, dated July 12, 1881.

Application filed March 24, 1881. (No model.)

To all whom it may concern:

Be it known that I, JOHN TAYLOR, a citizen of the United States, residing at Moorefield Junction, in the county of Hampshire and State 5 of West Virginia, have invented a new and useful Improvement in Fruit-Driers, of which the following is a full, clear, and exact description, reference being had to the accompanying drawings, forming part of this specification.

10 The object of my invention is to utilize the hot damp air that is generated in fruit-driers in such a way as to secure economy of fuel and greater uniformity of heat, and at the same time dry the fruit in a more rapid and perfect manner.

15 In the accompanying drawings, Figure 1 represents a perspective view of my invention; Fig. 2, a sectional elevation, and Fig. 3 a partial view of the rear portion of the furnace and flue.

20 A represents a casing for a fruit-drier, of any suitable size and shape, having its walls made hollow to form an air-chamber, a^3 , and provided with a hot-air flue, B, which incases the furnace-pipe b, said flue being arranged outside and extending from base upward to a point where it is provided with an outlet for the said pipe, and bending and opening downward into the top of the air-chamber. In the bottom 25 of said casing A is an enlarged portion of the air-chamber, provided with an interior air chamber or flue, a' , which is open at one end, for admitting the outer air, and connected at the other with hot-air flue B. Inside of this 30 interior air-chamber is a furnace, a^2 , having door a and communicating at its rear end with pipe b.

35 It will be seen that the heat of the furnace will cause a draft of air from without to enter 40 through the open end of air chamber or flue a' , which will pass up the flue B and down-

ward through the top of casing A into air-chamber a^3 , whence it will be forced by expansion through the perforated lining c into the fruit-chamber C. The said fruit-chamber is 45 provided with one or more perforated shelves, c^2 , through which the heated air passes down and becomes damp from absorbing the moisture in the fruit, and, in consequence of its increased weight and the pressure of the hot air 50 ascending the flue B, it falls through the valve c' and pipe c' in the bottom of said chamber into the furnace. As the furnace is thus fed with hot damp air, the heat is rendered more uniform than with a cold-air blast, and a less 55 expense of fuel is required on account of the vapor supplied to the furnace from the fruit; besides, the fruit is dried more rapidly and perfectly by having its moisture thus carried off.

Having thus described my invention, what 60 I claim as new, and desire to secure by Letters Patent, is—

1. In a fruit-drier, the casing A, having intermediate air-chamber a^3 and open-ended interior air chamber or flue a' , communicating with 65 flue B, in combination with a furnace and pipe, substantially as shown and described.

2. In a fruit-drier, the hot-air flue B, extending above the casing and inclosing the smoke-pipe b, in combination with a fruit-chamber 70 having a valve and pipe leading to the furnace, substantially as shown and described.

3. In a fruit-drier, a fruit-chamber, C, having perforated top and shelves, and valve c' and pipe c' in its bottom, in combination with 75 hot-air flue B and furnace a^2 , substantially as shown and described.

JOHN TAYLOR.
